(57) **CLAIM**

The ornamental design for a MOTORCYCLE FAIRING as shown and described.

DESCRIPTION

FIG. 1 is a top, front, left perspective view of a Motorcycle Fairing showing our new design;
FIG. 2 is a top, rear, right perspective view thereof;
FIG. 3 is a front elevation view thereof;
FIG. 4 is a left side elevation view thereof;
FIG. 5 is a right side elevation view thereof;
FIG. 6 is a top plan view thereof;
FIG. 7 is a bottom plan view thereof; and
FIG. 8 is a rear elevation view thereof.

The ornamental design which is claimed is shown in solid lines in the drawings. The broken lines shown illustrate portions of the Motorcycle Fairing that form no part of the claimed design.

1 Claim, 8 Drawing Sheets
